UNITED STATES PATENT OFFICE

ANESTIS FOLTIS, OF NEW YORK, N. Y.

DESIGN FOR A COMBINATION MATCH HOLDER AND ASH TRAY

Application filed December 9, 1929. Serial No. 33,709. Term of patent 3½ years.

To all whom it may concern:

Be it known that I, ANESTIS FOLTIS, a citizen of Russia, residing at New York, in the county of New York and State of New York, have invented a new, original, and ornamental Design for a Combination Match Holder and Ash Tray, of which the following is a specification, reference being had to the accompanying drawings, forming part thereof.

I claim:
The ornamental design for a combination match holder and ash tray as shown.

ANESTIS FOLTIS.
